UNITED STATES PATENT OFFICE.

OTTO CHARLES WINESTOCK, OF PERKINSVILLE, VERMONT.

SPARK-PLUG.

937,908.

Specification of Letters Patent.

Patented Oct. 26, 1909.

Application filed September 1, 1908. Serial No. 451,213.

To all whom it may concern:

Be it known that I, Otto C. WINESTOCK, a citizen of the United States, residing at Perkinsville, in the county of Windsor and State of Vermont, have invented a new and useful Spark-Plug, of which the following is a specification.

This invention has reference to improvements in spark plugs and its object is to provide for the better insulation and securing of the stem carrying the inner or central terminal.

The invention also includes means for the ready adjustment of the spark gap, the present invention relating more particularly to spark plugs of the jump spark type, and also provision is made by the present invention for preventing the accumulation of lubricating oil or of soot or of other materials liable to bridge the spark gap, upon the active end of the inner or insulated terminal.

The invention will be best understood from a consideration of the following detail description taken in connection with the accompanying drawings forming a part of this specification in which drawings,

Figure 1 is a longitudinal section of the improved spark plug with parts shown in elevation. Figs. 2, 3, 4, 5, 6 and 7 are detail views of different forms of the terminal end of the spark plug.

Referring to the drawings there is shown a member 1 in the general form usually provided for the cylindrical shell of a spark plug of the jump spark type and this shell has one end shaped into a neck 2 externally screw threaded to enter the usual screw threaded passage provided in the walls of the ignition chamber of an explosive engine for the introduction of the spark plug. Through the shell there is an axial passage, of less diameter where it extends through the neck 2 than at the other end of the shell 1, and between these two portions the axial passage is conical as indicated.

Both ends of the body portion are open and normally located within this body portion is a removable member 3 exteriorly shaped to seat in the axial passage through the member 1 and of such length as to extend slightly beyond each end of the said member 1. The removable member 3 is provided at diametrically opposite points with handles 4 by means of which it may be inserted in or removed from the body member 1, the

handles entering and being locked by suitably shaped slots in the body member 1, which slots however form no part of the present invention and are not shown in detail in the drawings.

The interior of the removable member 3 is formed with an axial passage which may be cylindrical at the lower end as indicated at 5 and then is made conical or tapering as indicated at 6 to the other or upper end 65 of said removable member 3.

Fitted within the tapering portion 6 of the bore of the removable member 3 is a tapering sleeve 7 of insulating material of equal thickness throughout so that the interior of the sleeve tapers like the exterior thereof, that is to say the interior walls of the sleeve and the exterior walls thereof are parallel one to the other.

The sleeve 7 receives the tapered end 8 of a stem 9 of conducting material extending beyond the smaller end of the sleeve 7 and there is threaded as shown at 10 to receive a suitable thumb nut 11 by means of which a suitable conductor may be electrically connected to the stem 9. The sleeve 7 extends for a distance beyond the corresponding end of the removable member 3 and there receives an insulating block 12 to the outer end of which is applied one or 85 more washers 13 and a clamp nut 14 screwed on the threaded end 10 of the stem 9. The nut 14 serves to force the washers 13 against the insulating block 12 and the latter against the corresponding end of the removable section 3. At the same time the stem 9 is drawn toward the nut 14 and this causes the tapered end of the stem 9 to tightly clamp the sleeve 7 in the tapered bore 6 of the member 3.

The larger end of the tapered portion 8 of the stem 9 does not extend to the corresponding end of the insulating sleeve 7 and this larger end is preferably bored and tapped to form a threaded socket 15 for the 100 reception of the threaded end of a rod 16 extending centrally through the smaller end of the removable member 3 and beyond said end, and there carries a disk 17 which may be riveted to the rod 16 in the form shown in Fig. 1 or may be otherwise attached thereto. In the structure shown in Fig. 1 the disk 17 is formed with an annular series of projecting teeth 18 extending laterally from one face of the disk and in operative rela- 110

tion to the corresponding end of the removable member 3, which end is annular and projects beyond the body 1 at this point.

The threaded socket 15 is of such depth 5 and the rod 16 of such length that the said rod may be screwed into or out of said socket and so bring the teeth 18 closer to or farther from the active end of the removable member 3. This active end which is 10 designated in the drawings by the reference numeral 19 becomes the fixed electrode of the spark plug while the toothed disk 17 becomes the adjustable electrode. By this means not only may the length of the spark 15 gap be adjusted at will but each time it is adjusted the points are brought opposite new portions of the fixed electrode, and thus the most efficient conditions are present each time the electrode 17 is adjusted. Furthermore, by providing a considerable space 20 between the active end 19 of the member 3 and the corresponding end of the insulation and tapered portion 8 of the stem 9, there is formed a chamber which is subjected to the 25 alternate action of compression and rarefaction as the piston of the engine reciprocates. The result of this is that there is more or less circulation established in the portion 5 of the bore of the member 3, and this tends 30 to keep this portion of the electrode free from the accumulation of any deleterious matters.

Instead of forming the disk 17 with teeth it may be formed as a plane disk as shown 35 at 20 in Fig. 2, although in this case the sparking points are not localized as in the case of the structure shown in Fig. 1.

Instead of using a plane disk as shown in Fig. 2, the disk may be somewhat dished as 40 indicated at 21 in Fig. 3, the surface presented toward the fixed electrode 19 being convex so that any oil or other matter which may reach this convex surface will tend to readily gravitate therefrom and thereby the 45 formation of soot between the electrode caused by the burning of the oil is prevented.

Instead of making the stem 16 carrying the electrodes 17, 20 or 21 adjustable in the stem section 8 the rod may be made in one 50 piece with said stem as shown at 22 in Fig. 4, and the free end of said rod may be threaded as indicated at 23 and a plane disk electrode 24 may be screwed thereon and held in adjusted positions by means of a 55 clamp nut 25 applied to the threaded end 23.

Instead of using a plane electrode 24 screwed upon the threaded end 23 of the rod extension 22 a convex electrode 26 similar to the electrode 21 of Fig. 3 may be screwed 60 upon the threaded end of the rod 22 as shown in Fig. 6, and the clamp nut 25 will then hold this electrode 26 in any adjusted position.

Since there are certain advantages in 65 using toothed electrodes, or at least one of

the electrodes toothed the fixed electrode may be toothed as indicated at 27 in Fig. 5.

While in the structure shown in Fig. 5 the form of electrode illustrated in Fig. 2 as a movable electrode, is shown in connection with the toothed fixed electrode 27 it will be understood that the structures of Figs. 3, 4 and 6 may be substituted therefor.

The tapering end 8 of the stem 9 engaging the tapering sleeve 7 causes the same to be 75 firmly seated against the tapering bore of the member 3 when the nut 14 is screwed down against the washer 13 and insulating block 12. There is thus provided a very broad bearing surface for the rather fragile 80 insulating material and without bringing too great pressure to bear upon this material a perfectly reliable gas tight joint is formed in this part of the structure and this joint is not at all liable to injury from the high 85 pressures generated within the explosion chamber of the engine.

It is to be observed that the movable electrode is of substantially the same diameter as the external diameter of the fixed electrode 19 so that the sparks must pass in a direction parallel with the axis of the movable electrode. This permits the lengthening or shortening of the spark gap by simply moving the electrode from or toward 95 the fixed electrode 19 in the structure of Fig. 1 or the fixed electrode 27 in the structure of Fig. 5.

In Fig. 7 the tapered end 8 is shown at 28 as split longitudinally and the stem 16' has 100 its threaded end 29 also tapered so that when screwed into the end 8 of the stem 9 the said end 8 is spread and so tightly forces the tapered sleeve 7 against the walls of the members 3. To facilitate the screwing of 105 the stem 16' into the end 8 the free or outer end of said stem is notched or slotted as shown at 30 to receive a screw-driver or other suitable tool.

The structure of Fig. 7 may be used in 110 connection with any of the forms of electrodes shown in the other figures, the electrode 31 shown in Fig. 7 being threaded to adjust on the threaded end 32 of the stem 16' and is there held by a nut 33.

What is claimed is:—

1. A spark plug having a central electrode stem with one end tapering, a removable member for said electrode, a tapering sleeve of insulating material interposed between the tapering end of the electrode stem and the removable member, said sleeve having parallel inner and outer walls, an annular fixed electrode, and a disk-like movable electrode exterior to and of greater diameter than the inner diameter of the fixed electrode said movable electrode being adjustable bodily to and from the fixed electrode in the direction of the longitudinal axis of the electrode to different active positions 130

relative to the said fixed electrode with the spark gap substantially constant throughout the active portions of the electrodes.

2. A spark plug having an annular fixed electrode, a central insulated stem extending through and beyond the fixed electrode and there threaded, and a disk-like electrode with a convex inner face, said electrode being threaded to screw upon said stem to and from the active end of the fixed electrode.

3. A spark plug having an external conducting member, a tapered sleeve of insulating material interior thereto, a taper member interior to said sleeve and provided with a split threaded socket, a stem with a taper threaded end adapted to enter the said threaded socket, and an electrode carried by the other end of the stem.

4. A spark plug having an external conducting member, a tapered sleeve of insulating material therein, a taper member interior to said sleeve and provided with a split threaded socket, a stem with a tapered

threaded end adapted to enter the said threaded socket and an electrode adjustable 25 longitudinally on said stem.

5. A spark plug having an external conducting member, a tapered sleeve of insulating material interior thereto, a taper member interior to said sleeve and provided with a split threaded socket, a stem with a taper threaded end adapted to enter the said threaded socket and having the other end threaded and provided with a notch for the reception of a screw-driver, an electrode carried by the notched threaded end of the stem, and a lock nut applied to the said notched threaded end of the stem in operative relation to the electrode.

In testimony that I claim the foregoing as 40 my own, I have hereto affixed my signature in the presence of two witnesses.

OTTO CHARLES WINESTOCK.
